UNITED STATES PATENT OFFICE.

WALTER H. HOST, OF KEENE, NEW HAMPSHIRE, ASSIGNOR TO NEWBURYPORT SILVER COMPANY, OF KEENE, NEW HAMPSHIRE, A CORPORATION OF NEW HAMPSHIRE.

DESIGN FOR A SPOON, FORK, OR SIMILAR ARTICLE.

46,880.

Specification for Design.

Patented Jan. 26, 1915.

Application filed October 20, 1914. Serial No. 867,660. Term of patent 3½ years.

To all whom it may concern:

Be it known that I, WALTER H. Host, a citizen of the United States, residing at Keene, in the county of Cheshire and State of New Hampshire, have invented a new, original, and ornamental Design for Spoons, Forks, and Similar Articles, of which the following is a specification, reference being had to the accompanying drawing, forming part thereof.

I claim:

The ornamental design for a spoon, fork or similar article, as shown.

WALTER H. HOST.
